No. 745,399.

PATENTED DEC. 1, 1903.

F. P. SOUDER.

REAMER.

APPLICATION FILED MAY 8, 1903.

NO MODEL.

UNITED STATES PATENT OFFICE.

FRANK POTTS SOUDER, OF BRIDGETON, NEW JERSEY.

REAMER.

SPECIFICATION forming part of Letters Patent No. 745,399, dated December 1, 1903.

Application filed May 9, 1903. Serial No. 156,483. (No model.)

To all whom it may concern:

Be it known that I, FRANK POTTS SOUDER, a citizen of the United States, residing at Bridgeton, in the county of Cumberland and State of New Jersey, have invented a new and useful Reamer, of which the following is a specification.

This invention is an improved construction of reamer to be used in packing canned goods in tin cans in which the top is soldered on, the object of the invention being to provide a simple and efficient device by means of which any surplus material may be removed from the can and also by means of which the material can be cleared away from the circular rim to which the top is soldered. When the material or liquid contacts with the under side of this circular rim, it tends to cool the solder and interferes with the sealing of the cans, and it is for the purpose of quickly and easily removing the surplus liquid and clearing away the material from the under side of the ring that the present construction of reamer has been devised, the advantages of such device being rapidity and simplicity of operation.

The invention consists, essentially, in the employment of a plug having apertures through which the surplus liquid can escape when the plug is forced into the circular opening in the top of the can, said plug being carried by a rotatable spindle and carrying a wiper-finger which is adapted to be projected laterally when the plug is rotated.

The invention consists also in the means for projecting the wiper-finger and rotating the plug, and the invention also consists in certain details of construction and novelties of combination, all of which will be fully described hereinafter and pointed out in the claims.

In the drawings forming part of this specification, Figure 1 is a perspective view showing the practical application of my invention. Fig. 2 is a vertical sectional view, partly in elevation, showing the positions of the various parts before inserting the plug in the top of the can. Fig. 3 is a sectional view, partly in elevation, showing the position the parts assume during the operation. Fig. 4 is a sectional view on the line 4-4 of

Fig. 3. Fig. 5 is an inverted plan view of the plug, the wiper-finger being shown in the position indicated in Fig. 2. Fig. 6 is a detail perspective view showing the end of the 55 rod, the wiper-finger pivoted thereto, and the suspending link which is connected to the wiper-finger.

In carrying out my invention I employ a plug A, which may be made of any suitable 60 material and tapered slightly, so that it can be easily inserted in the central opening at the top of a can B. The bottom of this plug is concaved, as shown at A', and communicating with this concavity are the bores A², 65 leading from the sides of the plug, and the bores A³, leading to the top of the plug, said concavity and bores permitting surplus liquid to be forced from the can when the plug is inserted therein. The plug is rigidly connected to the tubular spindle C, said spindle having collars C' and C² arranged upon the exterior thereof adjacent the lower end and between which is arranged the supporting-plate D, having feet D', which rest upon the 75 circular ring B' of the can when the plug is inserted in the circular opening, the spindle being rotatable in the supporting-plate, and consequently causing the plug to rotate in the central aperture, as more fully explained 80 hereinafter.

A rod E is arranged in the tubular spindle C, said rod extending entirely through the spindle, it being of slightly-greater length than the said spindle, and carries at its lower 85 end a wiper-finger F, which is pivotally connected to a rod at F'. This finger is also pivotally connected to a link G, said link being suspended by a cross-pin G', which rests upon the top of the plug, the link and wiper-finger 90 operating in the radial slot A', produced in the plug, said slot extending from the concavity of the plug to the top and side thereof, as most clearly shown in Fig. 2. This wiper-finger being connected to the rod and 95 suspended by the link will be elevated and projected laterally, as shown in Fig. 3, whenever the rod E is pressed downwardly, and it will of course be understood that this rod is pressed downwardly after the plug has been 100 inserted in the top of the can, and after the finger has been projected outwardly, as shown

in Fig. 3, the plug is rotated, carrying with it the said finger, and all of the material which rests adjacent the under side of the circular ring B' will be wiped therefrom, so that when the plug is removed there will be no material or liquid contacting with the ring, and consequently the soldering operation can be carried on without chilling the solder.

10 For the purpose of rotating the plug I provide spiral grooves C³ in the upper portion of the spindle C, and arranged upon said spindle is a sliding block or handle H, having plates H', attached to the top thereof, carrying pins H², which work in the spiral grooves, and it is obvious that by moving the sliding block or handle up or down the spindle will be rotated, carrying with it the plug, the spindle and block being supported in their proper positions by means of the supporting-plate D, which rests upon the top of the can, as most clearly shown in Figs. 1 and 3. The upper end of the spindle is provided with a laterally-extending lug C⁴ for the purpose of affording sufficient grip upon the spindle while pressing downwardly upon the upper end of the rod E. For the purpose of projecting the wiper-finger laterally after the plug has been inserted in the top of the can 20 and for the purpose of holding the rod elevated and the finger withdrawn I employ a spring-catch I, having a nose I', adapted to engage a notch E', produced in the side of the rod adjacent the upper end, and it will also be noted that this spring-catch has an overlapping end I², which rests upon the upper end of the rod when the said rod is locked in a raised position. The upper portions of the spiral slots are made straight, as shown at 25 C⁵, and the rod is provided with pins E², which travel in the spiral slots and which are engaged by the pins H² during the last portion of the upward movement of the sliding block or handle, and while the pins H² are traveling in the straight portion E⁵ of the slots C⁵ the engagement of the pins H² with the pins E² serves to elevate the rod and withdraw the wiper-finger to the position shown in Fig. 2, so that the plug can be removed from the can.

30 From the above description, taken in connection with the accompanying drawings, it will be clearly understood that when the reamer is inserted in the can the surplus liquid will be forced through the plug and in that manner removed from the can. The reciprocation of the sliding block or handle upon the spiral-groove spindle serves to rotate the spindle, and the downward movement of the rod within the spindle 35 serves to project the wiping-finger laterally beyond the sides of the plug, and the rotation of the plug with the finger in such projected position serves to wipe away all of the material from the under side of the circular ring forming the top of the can. A spiral spring K surrounds the spindle between the

bearing-plate and lower end of the sliding block or handle for the purpose of returning the said block automatically as soon as pressure is relieved therefrom.

70

While I have shown my improved construction of reamer as a separate device and independent of any operating mechanism, it is obvious that it can be arranged in connection with any suitable construction of machine or operating mechanism and that instead of being arranged singly it can be arranged in any desired number and all capable of operation simultaneously.

75

Having thus fully described my invention, what I claim as new, and desire to secure by Letters Patent, is—

80

1. A reamer for the purpose described comprising an apertured and slotted plug, the wiper-finger suspended in the plug adapted to be projected laterally through the slot of said plug, the rod to which the wiper-finger is connected, the spindle carrying the plug and in which the rod is arranged, together with means for rotating the spindle, substantially as described.

85

2. A reamer of the kind described comprising a plug having apertures therein, and a radial slot, a tubular spindle connected to the plug, said tubular spindle turning loosely in a support, a rod arranged in the tubular spindle, a wiper-finger pivotally connected to the lower end of said rod, a link suspended in the radial slot and pivotally connected to the wiper-finger and means for moving the rod up and down within the spindle together with means for rotating said spindle, substantially as described.

90

3. A reamer of the kind described comprising the plug having apertures therein, and a radial slot and spindle connected to the plug, a support in which the spindle rotates, the upper portion of said spindle having spiral grooves cut therein, a reciprocating handle arranged upon the spindle and carrying pins which engage the spiral grooves, the rod arranged within the spindle, the wiper-finger pivotally connected to the lower end of the rod, the link suspended in the slot and pivotally connected at its lower end to the wiper-finger, together with means for raising and lowering the rod, and means for holding the said rod in a raised position, substantially as described.

95

4. A reamer of the kind described, comprising the plug having apertures therein and a radial slot, a tubular spindle rigidly connected to the plug and having spiral grooves in the upper portion thereof, a laterally-projecting lug at the upper end thereof, a supporting-plate provided with feet, the tubular spindle being rotatably held in said plate, the rod arranged in the tubular spindle, the wiper-finger pivotally connected to the lower end of the rod, the suspended link arranged in the plug and pivotally connected at its lower end to the wiper-finger intermediate its
